JULIUS H. RICHARDS, OF TORRINGTON, CONNECTICUT, ASSIGNOR TO ECLIPSE MACHINE COMPANY, OF ELMIRA, NEW YORK, A CORPORATION OF NEW YORK

ENGINE STARTER

Application filed October 18, 1923. Serial No. 669,202.

My invention relates to a starter for starting internal combustion engines or the like and the same pertains more particularly to the drive or transmission located between the prime mover such as an electric motor and a member of the engine to be started such as the flywheel thereof. The object of my invention is to provide a comparatively simple but efficient and reliable drive of this character, whose advantages in construction and mode of operation will be apparent from the description hereinafter given.

In the drawings, Figure 1 is a sectional elevation of a starting apparatus including, in addition to the drive, a portion of the motor and of the flywheel; Fig. 2 a plan view of the drive barrel detached; Fig. 3 a section on the line 3—3 of Fig. 2; Fig. 4 an elevation of one set of the clutch plates; Fig. 5 an elevation of one of the other set of clutch plates; Fig. 6 an elevation of the screw shaft detached; Fig. 7 a section on the line 7—7 of Fig. 6; Fig. 8 an elevation of the locking rings; Fig. 9 an elevation of one end of the drive sleeve and Fig. 10 a side elevation thereof partly in section.

In the present instance, I have shown my invention embodied in a drive of the outboard type and also of the direct drive type, although it will be understood that the same is applicable to the inboard type and also to the indirect drive type.

Referring to the embodiment of my invention as herein shown, the electric starting motor M is provided with an extended armature shaft 1 on which is loosely mounted a hollow screw shaft or sleeve 2. This shaft is provided at a point adjacent the motor with an enlargement 1^a to which is secured by the bolt 29 a drive sleeve 11 which extends forwardly towards the screw shaft and has the particular shape illustrated in Figs. 9 and 10. This sleeve has an out-turned marginal flange 12 which is provided with marginal extensions 27 and intervening recesses 28, in order to engage the longitudinal slots 19 of the barrel 3, with the result that the drive sleeve will rotate the barrel but the latter will have a relative longitudinal movement with re-

spect thereto. In short, the barrel and sleeve are splined to each other.

Between the drive sleeve 11 and the screw shaft 2 there is interposed a friction clutch comprising a set of clutch plates 5 having extensions 24 and intervening recesses 25 co-operating with the slots 19 of the barrel, and also a set of plates 6 having inward extensions 26 and intervening recesses 20 to co-operate with the longitudinal grooves 23 of the screw shaft. Thus the plates 5 are in positive engagement with the barrel and frictional engagement with the sleeve 11 and the plates 6 are in positive engagement with the screw shaft. By reason of the slots 19, the barrel has a relative longitudinal movement with respect to the clutch and by reason of the grooves 23 the screw shaft also has a relative movement with respect to such clutch, which latter movement is against the tension of a coil spring 30 located within the bore of the sleeve 11 and between the enlargement 1^a and the inner end of the screw shaft. The plates are held in frictional engagement by means of the coil spring 4 located within the barrel and interposed between the clutch and the front end of the barrel. In order to hold the barrel in place and limit its outward movement, I provide locking rings or keys 13 having extensions and intervening recesses to co-operate respectively with the slots 21 and those portions 22 of the barrel between the slots 19 as illustrated in Figs. 2 and 8.

The driving member which is here in the form of a pinion 7 is threaded upon the screw shaft 2 and is thereby mounted for longitudinal movement thereof into engagement with the flywheel teeth 10 and for rotary movement therewith after being arrested in its longitudinal movement by the stop nut 8 at the outer end of the screw shaft. The armature shaft is provided with a bearing at its outer end in a bracket 9 which is attached to or forms an extension of the frame of the electric motor M.

Describing the operation and starting with the parts in their normal position shown in Fig. 1, when the motor is energized by the actuation of the switch (not shown) the shaft 1 is rotated with the result that the sleeve 11, 100

friction clutch, barrel and screw sleeve are rotated, thereby causing the pinion 7 to advance longitudinally into mesh with the flywheel. When this longitudinal movement has been arrested by the stop nut 8, the pinion will partake of the rotary movement of its screw shaft and the flywheel will be rotated. As soon as the engine starts on its own power, the pinion will be demeshed in the usual and well-known manner.

In the event that perfect mesh between the pinion and the flywheel teeth should not occur and such teeth should abut end to end, the pinion will be thereby arrested in its longitudinal movement, but the screw action will continue with the result that such shaft will be moved longitudinally to the right, Fig. 1, against the tension of the spring 30. This longitudinal movement is permitted by reason of the length of the slots or grooves 23 in the screw shaft. Upon sufficient longitudinal movement of this screw shaft, the pinion will be caused to rotate slightly and thereby bring about perfect register between the teeth whereupon the spring 30 will restore such shaft to normal position and the pinion will be screwed into full mesh by the rotation of its shaft.

The spring 4 is of sufficient strength to cause the clutch to take somewhat more torque than the motor used is capable of supplying, but such spring will permit the clutch to slip if more torque is applied than the clutch is capable of transmitting. It will be understood that the pinion is threaded upon the screw shaft and is not connected with the barrel, but is normally enclosed thereby and free to move outwardly thereof and inwardly through the front opening 14 thereof.

40 I claim:

1. An engine starter drive including a rotatable shaft, a driving member mounted thereon for longitudinal movement thereon and for rotary movement therewith, a driving shaft, a friction clutch operatively connected with said two shafts, and a barrel enclosing the clutch and the driving member when the latter is in its normal position but permitting such driving member to move longitudinally outwardly.

2. An engine starter drive including a rotatable screw shaft, a pinion threaded thereon for longitudinal movement thereon and for rotary movement therewith, a rotatable driving shaft, a friction clutch operatively connected with the driving shaft and splined to the screw shaft, and a barrel splined to the clutch and enclosing the same and also enclosing the pinion when it is in its normal position.

3. An engine starter drive including a rotatable driving shaft, a hollow shaft mounted thereon and rotatable therewith but capable of independent rotary movement, a driving member mounted on the hollow shaft for

longitudinal movement thereof and rotary movement therewith, a sleeve secured to the driving shaft, a friction clutch interposed between such sleeve and the hollow shaft and splined to the latter, a barrel enclosing and connected with the clutch, and a spring arranged within the barrel and between it and the clutch.

4. An engine starter drive including a rotatable driving shaft, a hollow shaft mounted thereon and rotatable therewith but capable of independent rotary movement, a driving member mounted on the hollow shaft for longitudinal movement thereof and rotary movement therewith, a sleeve secured to the driving shaft, a spring located within the sleeve and bearing against one end of the hollow shaft to yieldingly hold it in normal position longitudinally, and a friction clutch interposed between such sleeve and the hollow shaft and splined to the latter.

5. An engine starter drive including a rotatable screw shaft, a pinion threaded thereon for longitudinal movement thereon and for rotary movement therewith, a rotatable driving shaft, a friction clutch operatively connected with the driving shaft and splined to the screw shaft, and a barrel splined to the clutch and enclosing the same and also enclosing the pinion when it is in its normal position, said barrel having a front opening through which the pinion freely passes in its longitudinal movements.

6. An engine starter drive including a rotatable driving shaft, a hollow shaft mounted thereon for relative longitudinal movement, a driving member mounted on the hollow shaft for longitudinal movement thereof and rotary movement therewith, a sleeve secured to the driving shaft and spaced apart therefrom to form an annular space to receive the hollow shaft in its longitudinal movement, and a driving connection between the sleeve and hollow shaft.

7. An engine starter drive including a rotatable driving shaft, a hollow shaft mounted thereon for relative longitudinal movement, a driving member mounted on the hollow shaft for longitudinal movement thereof and rotary movement therewith, a sleeve secured to the driving shaft and spaced apart therefrom to form an annular space to receive the hollow shaft in its longitudinal movement, a spring in such annular space tending to resist such longitudinal movement, and a driving connection between the sleeve and hollow shaft.

8. An engine starter drive including a rotatable driving shaft, a hollow shaft mounted thereon for relative longitudinal movement, a driving member mounted on the hollow shaft for longitudinal movement thereof and rotary movement therewith, a sleeve secured to the driving shaft and spaced apart therefrom to form an annular space to receive

the hollow shaft in its longitudinal movement, and a friction clutch interposed between such sleeve and hollow shaft and operatively connected therewith.

5 9. An engine starter drive including a rotatable driving shaft, a hollow shaft mounted thereon for relative longitudinal movement, a driving member mounted on the hollow shaft for longitudinal movement thereof and rotary movement therewith, a sleeve secured to the driving shaft and having an end flange, and a friction clutch interposed between such flange and the hollow shaft and operatively connected with the latter in all longitudinal positions of the latter.

10 10. An engine starter drive including a rotatable driving shaft, a hollow shaft mounted thereon for relative longitudinal movement, a driving member mounted on the hollow shaft for longitudinal movement thereof and rotary movement therewith, a member fixed to said driving shaft and forming an abutment with respect to which said hollow shaft is movable, and a friction clutch operatively connecting said member and said hollow shaft, said clutch abutting against said member and permitting relative longitudinal movement of said hollow shaft.

15 11. An engine starter drive including a rotatable driving shaft, a hollow shaft mounted thereon, a driving member mounted on the hollow shaft for longitudinal movement thereof and rotary movement therewith, a member fixed against longitudinal displacement on said driving shaft and forming an abutment, a friction clutch operatively connecting said member and said hollow shaft and constantly abutting against said member, said hollow shaft being longitudinally movable with respect to said driving shaft, clutch and abutment member, and means for normally positioning said hollow shaft at one end of its range of longitudinal movement.

45 JULIUS H. RICHARDS.
